INVENTOR

EDWARD A. BUELL

BY *Manus Co.*
ATTORNEYS

UNITED STATES PATENT OFFICE.

EDWARD A. BUELL, OF NORFOLK, VIRGINIA.

RAILROAD-TRACK.

No. 925,285.

Specification of Letters Patent.

Patented June 15, 1909.

Application filed December 5, 1906. Serial No. 346,386.

To all whom it may concern:

Be it known that I, EDWARD ALEXANDER BUELL, a citizen of the United States, and a resident of Norfolk, in the county of Norfolk and State of Virginia, have invented certain new and useful Improvements in Railroad-Tracks, of which the following is a specification.

My invention is an improvement in railroad tracks, particularly in the ties and the cushioning and fastening devices; and the invention consists in certain novel constructions and combinations of parts as will be hereinafter described and claimed.

In the drawing Figure 1 is a perspective view of a section of track embodying my invention. Fig. 2 is a top plan view thereof. Fig. 3 is a cross-section on about the line 3—3 of Fig. 2. Fig. 4 is a section on about the line 4—4 of Fig. 2. Fig. 5 is a detail perspective view of the cap for the cushion block. Fig. 6 is a detail perspective view of the cushion block. Fig. 7 shows the block with its cap or plate. Fig. 8 is a detail view partly broken away of the rail holding bar, and Fig. 9 is a cross-section of the cushion block showing the sectional construction thereof.

By my invention I provide a tie A of concrete in which is embedded a bar or bars B extending longitudinally of the tie and preferably two in number arranged as indicated in dotted lines Figs. 2 and 3 between the rails C and having at their ends upwardly projecting lugs B' and B'' which extend up above the upper surface of the tie A and lying on opposite sides of the rails C, prevent the lateral movements of said rails in either direction, thus preventing the spreading of the rails, as will be understood from Figs. 1, 2 and 3 of the drawing. I also provide rail fastening blocks D and bolts D' for securing the same, said bolts extending vertically through the concrete tie and through the rail fastening blocks D as shown in Figs. 3 and 4 of the drawing.

In this class of ties, it is quite important to cushion the rails and in doing this I seek to provide means whereby the cushioning medium may be prevented from spreading and be retained so that as the cushion is retained or confined its entire cushioning effect may be produced upon the rail and in addition to thus securing a better cushioning

effect I provide a construction which will be more lasting and durable as is of utmost importance. To this end I employ a cushion block E which may be of wood or other suitable material and which may be made in upper and lower sections, as shown in Figs. 6 and 9 or may if desired be made in one section as shown in Fig. 7. These cushion blocks are placed in recesses or pockets a formed in the upper surface of the tie A and preferably of a width equal to the width of the rail base C' and of a length less than the width of the tie, see Fig. 4, so that the block E will be retained on all four sides within the cavity or recess a to which it is fitted, as shown in Figs. 3 and 4 of the drawing. To prevent any spreading of the block at its upper end I provide on said end a metallic cap plate F which rests upon the upper side of the cushion block, fits within the upper end of the mouth of the recess or pocket and projects above the surface of the tie to form a seat for the rail C. The block is of a height to terminate about three-quarters of an inch below the upper face of the tie, and the plate F is preferably about one inch thick so it will extend above the face of the tie to support the rail clear of the concrete and in case the block should be compressed to too great an extent at any time, the steel or other metal plate may be lifted and a small piece of iron or other filling be inserted beneath it as shown at G in Fig. 9 of the drawing.

By the described construction it will be noticed that the cushioning block of wood is confined in the recess and the metal cap which confines the cushion in the recess projects into said recess so that no portion of the cushion block is exposed and the elasticity of the block is wholly available or fully utilized.

It may be preferred in some instances to make the cushion block in upper and lower sections as shown in Figs. 6 and 9 so that should either section require to be replaced it can be done without inserting an entirely new one.

As before suggested the width of the recess and of the cushion block is equal to the width of the rail base.

As will be understood from Figs. 2 and 4 the upwardly projecting lugs of the securing bars B are arranged at the opposite ends of

the recesses *a* for the cushion blocks and the intermediate portions *b* of said bars extend along the opposite ends of the recesses and reinforce the end walls thereof, as will be understood from Figs. 2, 3 and 4.

5 By the described construction it will be noticed I provide a concrete tie in which the cushion arranged directly below the rail bearing is entirely incased or confined. This 10 is important as by entirely incasing or confining the cushion all the elasticity is available and may be utilized, thus securing the desired cushioning effect without any loss of elasticity in the cushion block.

15 I claim:—

1. The combination substantially as herein described of the concrete tie having embedded therein the longitudinally extending securing bars provided at their ends with the 20 upwardly projecting lugs extending above the face of the tie and adapted to rest on the opposite sides of the rail base and provided between the securing bars with recesses or pockets of a width equal to the width of the 25 rail base, means for securing the rails to said tie, cushion blocks fitting in the recesses, and cap plates fitting within the upper ends of the recesses upon the upper sides of the cushion blocks and projecting above the

upper face of the tie to form seats for the 30 rails, substantially as set forth.

2. A concrete tie having recesses or pockets in its upper face and cushion blocks therein and composed of upper and lower sections, and having rail holding bars extending longitudinally within the tie and having at their ends upwardly projecting lugs to lap along the opposite sides of a rail base with portions of the holding bars intermediate the lugs at each end extending along 40 the opposite ends of the cushion blocks, substantially as set forth.

3. A concrete tie provided in its upper face with recesses and having rail holding bars extending past the opposite ends of the recesses and provided at the inner and outer sides of said recesses with upwardly projecting lugs to project along the opposite sides of the rail base, cushion blocks in said recesses, and cap plates fitting at their lower 50 sides in the ends of the recesses and projecting at their upper faces above the upper surfaces of the tie, substantially as set forth.

EDWARD A. BUELL.
